UNITED STATES PATENT OFFICE.

JOHN H. FOSTER, OF CUTHBERT, TEXAS.

CULTIVATOR.

1,073,672.

Specification of Letters Patent. Patented Sept. 23, 1913.

Application filed December 11, 1911. Serial No. 665,168.

To all whom it may concern:

Be it known that I, JOHN H. FOSTER, citizen of the United States, residing at Cuthbert, in the county of Mitchell and State of Texas, have invented certain new and useful Improvements in Cultivators, of which the following is a specification.

My invention relates to new and useful improvements in cultivators.

10 The object is to provide a cultivator having plow beams mounted in such a manner that they may be simultaneously subjected to angular displacement by the operator, so that they may be momentarily diverted to a different direction of travel from that of the machine thus making it possible for the operator to avoid striking stones, roots or other obstructions without the necessity of deviating the entire machine from its path.

15 A further object of the invention is to provide a mechanism that may be adjusted to limit the swing of the beams.

20 Finally the object of the invention is to provide a device of the character described that will be strong, durable, simple and efficient and comparatively easy to construct, and also one, the various parts of which will not be likely to get out of working order.

25 With these and various other objects in view, my invention has relation to certain novel features of the construction and operation, an example of which is described in the following specification and illustrated in the accompanying drawings, wherein:—

30 Figure 1 is a plan view of a cultivator in which are embodied the novel features constituting the present invention. Fig. 2 is a rear view of the same. Fig. 3 is a side elevation of the same. Fig. 4 is a detail sectional view of a pivotal joint by which standards supporting the transporting wheels are attached to the frame of the machine, the section for said view being taken upon the line X X of Fig. 3. Fig. 5 is a detailed sec- 35

40

45

50

tional view of a clamping device, one of which is employed to attach each plow standard to the correlated plow-beam. Fig. 6 is a detailed view showing a special form of spindle employed to receive the transport- 45

50

ing wheels, said spindle being adapted to be removed and replaced when worn out.

Referring now more particularly to the drawings wherein like numerals of reference designate similar parts in all the figures, the 55 numeral 1 denotes the two transporting wheels each of which is mounted upon a

spindle 2 having its inner extremity threaded and received by a threaded socket 3 provided in the out turned lower extremity of an upright 4. The two standards 4 are of equal height and each is surmounted by a bracket member 5, which in conjunction with the correlated standard 4 forms a T. To each of the bracket members 5 are rigidly attached the rear portions of a pair of parallel frame members 6, having their forward extremities pivotally connected by a transverse bar 7. The rear ends of the bars 6 project a slight distance beyond the members 5, and are each provided with a plurality of bolt holes 8, adapted to receive bolts which form pivots for the forward lower extremities of arms 9, carrying upon their upper rear extremities a transverse bar 10, (commonly known as a saddle bar) provided with a seat 11 at its center. The bolts by which the members 9 are pivotally attached to the members 6, are designated by the numeral 12, and the numeral 13 denotes bolts adapted to furnish a support for the bars 9 to hold the same at the proper angle. When it is desired to adjust the rear plows of the cultivator the bars 9 may be swung to a vertical position thus preventing the seat from offering any hindrance to the operator working at the rear of the machine.

A pin 14 preferably integral with each standard 4 projects above said standard, and receives one arm of an angular pipe 15, the other arms of said pipe being turned inward, and oppositely positioned. Said inwardly turned arms are received by the extremities of a pipe 17 and can be adjusted laterally therein.

From the above description it is apparent that the distance between the wheels is subject to regulation between certain limits. Beneath the bar 7 is attached an arch bar consisting of a horizontal member 18, and a pair of downwardly extending members 19, having their lower ends outwardly turned as indicated at 20. To each of the parts 20 is pivotally secured the forward end of a cultivator beam 21, extending rearwardly in the usual manner. To each beam are attached a plurality of plow shanks 22, by means of clamps 23. A pair of braces 24 inclined upwardly from front to back have their forward extremities pivotally attached to the parts 20 and the rear extremities hinged upon the upright standards 4. A pair of bars 25 have their rear extremities

clamped upon the pipe 17, and after extending forwardly a short distance beyond the bar 7, the bars 25 turn inwardly and are secured to the rear end of the tongue 26. 5 A transverse bar 27 is centrally mounted beneath the rear end of the tongue and has its extremity connected by brace rods 28 with the members 20. From the rear extremities of the beams 21 a pair of balance bars 29 10 extend upwardly being provided with grips 30 near their upper ends. The upper extremities of said bars have pivotal connection through rods 31 with the pipe 17. A pair of coiled springs 32 establish a connection between the upper portions of the rods 31 and the cross bar 27. The parts 29, 30, 15 31 and 32 are not claimed as a part of this invention since they are already in common use, and are shown merely to present a complete machine. 20

Upon the tongue adjacent to the rear of the end thereof is slidably mounted a weight 33, guided in its motion by a pair of plates 34. This weight which is intended to act 25 as a counter balance to the weight of the driver, is adapted to be adjusted by means of a lever 35 to which the weight is pivotally attached by a rod 36.

Upon the forward extremities of the bars 30 6 are mounted a pair of angular members 37, each having one of its parts slotted as indicated at 38. The members 37 are mounted on the bars 6, suitable fastenings being passed through the slots 38 and secured in the bars. The angular portions of the members 37 are directed inward longitudinally of the bar 7. By adjusting the members 37 toward and from the bar 7 the amplitude of the arc in which the bars 6 40 swing, may be regulated, and by adjusting the members so that they contact with bar 7, the bars 6 may be fastened in fixed relation to said bar 7. Owing to the connection established between the bars 6 and the beams 45 21, any motion to which one of the members is subjected will be communicated to the other.

The important feature of the invention lies in the fact that the cultivator beams may

be shifted at an angle with the direction 50 of travel so that the plows may be made to avoid any small obstacle such as a stone or a root without requiring the driver to deviate the machine from its path. The driver will accomplish each adjustment by pressing with his foot against one of the beams and at the same time manipulating the upright bars 29.

The invention is presented as including all such changes and modifications as come 60 within the scope of the following claims.

What I claim is:—

1. A cultivator comprising a pair of transporting wheels, a pair of standards upon the lower extremities of which the transporting 65 wheels are rotatably mounted, a pair of parallel bars having their rear extremities pivotally mounted upon the upper ends of said standards, a cross bar pivotally connecting the forward extremities of said bars, 70 an arch bar attached to said cross bar, a pair of cultivator beams extending rearwardly from the lower extremities of the arch bar, and a pair of adjustable right-angled brackets mounted on said parallel 75 bars and bearing against said cross bar.

2. A cultivator comprising a pair of transporting wheels, a pair of standards upon the lower extremities of which the transporting 80 wheels are rotatably mounted, a pair of parallel bars having their rear extremities pivotally mounted upon the upper ends of said standards, a cross bar pivotally connecting the forward extremities of said bars, 85 an arch bar attached to said cross bar, a pair of cultivator beams extending rearwardly from the lower extremities of the arch bar, and a pair of adjustably slotted brackets mounted on said parallel bars and arranged to bear against said cross bar. 90

In testimony whereof I have signed my name to this specification in the presence of two subscribing witnesses.

JOHN H. FOSTER.
